INVENTOR.

L. M. Rees.
BY Edward Mayber.
ATTY.

UNITED STATES PATENT OFFICE.

LLEWELYN MORRIS REES, OF HAMILTON, ONTARIO, CANADA.

WEATHER-STRIP.

1,352,695.

Specification of Letters Patent. Patented Sept. 14, 1920.

Application filed September 12, 1919. Serial No. 323,311.

To all whom it may concern:

Be it known that I, LLEWELYN MORRIS REES, a subject of the King of Great Britain, and resident of the city of Hamilton, 5 in the county of Wentworth, Province of Ontario, Canada, have invented certain new and useful Improvements in Weather-Strips, of which the following is a specification.

10 This invention relates to weather strips for doors of the type in which the closure of the door moves the weather strip into contact with the threshold to effectively close any gap between the door and threshold, 15 and my object is to devise a weather strip of this type which will be simple, durable and effective, the movable part being so arranged and moved as to very effectively seal the gap.

20 I attain my object by means of the constructions hereinafter described and illustrated in the accompanying drawings in which—

Figure 1 is a front elevation, partly 25 broken away, showing part of a door provided with my improved strip;

Fig. 2 a cross section of the same;

Fig. 3 a perspective view of the guide plate and spring attached; and

30 Fig. 4 a detail in cross section.

In the drawings like numerals of reference indicate corresponding parts in the different figures.

1 is part of a door of which 2 is a door 35 frame and 3 the threshold. The weather strip frame is formed of two triangular metal end frames 4 and a transverse wooden strip 5. This transverse strip 5, is secured to the door 2 by means of screws. The end 40 frames are provided with flanges 6 to secure them to the transverse strip 5, the flanges being provided with screw holes for that purpose.

A movable wooden strip 9 is arranged to 45 slide between the face of the door and the flanges 6. Preferably the flanges are notched intermediate their ends to allow springs 26, which are secured to the upper portion of the flanges 6 by means of screws 28, to bear 50 against the movable strip.

I show a plate 8 as provided with a third bent spring 26 secured thereto and operating through an opening cut in the plate. The springs tend to press the wooden strip 55 in toward the door.

In the case of very wide doors one or more

springs 26 may be used intermediate the plate 8 and flanges 6 bearing on the strip 9 and secured directly to the strip 5.

The movable strip is operated by the following means. Normally the wooden strip is retracted by coil springs 11, which are fitted in notches in the removable and fixed strips and secured at their ends to said strips. To depress the movable strip when the door is closed I provide the following mechanism. A rock shaft 13 is journaled in the end frames and has secured thereto rock arms 14 which have rounded under faces engaging the upper edges of the movable strip 9. This edge has preferably shallow notches formed therein to bring the downward push of the arms more in the direction of movement of the strip. The rock arms are preferably rotarily adjustable on the rock shaft 13 and secured in position by set screws 15 and bolts 29 passing through the shaft and through slots in the hubs of the arms. This enables me to cause one end of the strip to be thrown down farther than the other in cases where the gap between the door and threshold is not of even width from end to end. The rock shaft is actuated through the medium of a rock arm 16 which is secured to one end or the other according as the door is a right or left hand opening door. This arm is extended out so as to engage the door frame, which is preferably provided with a spring rubbing plate 17 to take the wear of the arm. The arm is preferably adjustable in length, the movable end being formed by a screw 18 threaded into the arm. By adjusting this screw the throw of the movable strip may be regulated. Preferably the arm is secured to the rock shaft by means of a set screw 20, where further adjustment can be made if desired.

For neatness of appearance and to exclude dirt, any suitable cover may be secured over the device.

What I claim as my invention is:—

1. In a weather strip, the combination of a transverse wooden strip adapted to be secured to the face of a door; metal end frames provided with flanges secured to said wooden strip; a vertically movable strip fitted below the fixed strip and behind the end frames; a rock shaft journaled in the end frames; rock arms on said shaft adapted to engage the upper edge of the movable strip; a rock arm on said shaft the end of which is adapted to engage the door

jamb to rock the shaft and thus depress the movable strip; springs connected to the fixed strip and the movable strip and tending to raise the latter; and springs tending to press the movable strip toward the door.

2. A weather strip constructed as set forth in claim 1 provided intermediate its ends with a guide plate secured to the fixed strip having a slot therein and a bent spring

secured to said plate and operating through said slot to press the movable strip toward the door.

Signed at Hamilton, Ontario, this 19th day of August, 1919.

LLEWELYN MORRIS REES.

Witnesses:

EDWARD KING,

THOMAS LOCKHEAD.
